UNITED STATES PATENT OFFICE.

WILLIAM H. G. GEAKE, OF SYDNEY, NEW SOUTH WALES, AUSTRALIA, ASSIGNOR TO
WALTER RUTHERFORD, OF LONDON, ENGLAND, AND JOHN BAIN, OF OTTAWA,
CANADA.

COMBINATION CONTAINER AND GREASE GUN.

Application filed December 16, 1925. Serial No. 75,851.

My invention relates to improvements in combination containers and grease guns, the objects of which are to provide means whereby semi-fluid greases and the like may be packed to sell and the container used by the purchaser as a grease gun by which the grease is delivered under suitable pressure, to provide for a structure which is of such economical manufacture as will permit of the container being discarded after use, and to provide means whereby sufficient force may be applied to the contents to eject it irrespective of its consistency, further objects are to provide against leakage of the contents of the container between the piston and the side walls of the container or through the operating shaft bearings, and also to prevent the inadvertent movement of the operating means.

The invention consists essentially of a container having a seamed or screw top in which a piston is slidably mounted and flexible tensioning means for raising the contents of the container and ejecting it through a delivery nozzle, as will be more fully described in the following specification, in which:—

Fig. 1 is a sectional view of one embodiment of the invention.

Fig. 2 is a sectional view of a modification.

Fig. 3 is a sectional view of a further modification.

Fig. 4 is a sectional view of a further modification showing an operating shaft mounted outside the body of the container.

Fig. 5 is a sectional view taken on the line 5—5 of Figure 1.

Fig. 6 is a plan view of the bale taken on the line 6—6 of Figure 2.

In the drawings like characters of reference indicate corresponding parts in each figure.

The numeral 1 indicates generally a container preferably made, for purposes of economy, according to regular can practice. 2 are the side walls, 3 the bottom closure, 4 a top closure, which may be seamed to the side walls as shown in Figures 1, 3 and 4, or formed with a screw top as at 5, see Figure 2. In the top closure 4 a small cap 6, open to the container body 1 is fitted, and from this cap a discharge nozzle 7 extends, which may be of any suitable shape or length. In opposite side walls of the cap

I provide respectively a capped bearing 8 and an open-ended bearing 9, which are preferably similar to a hollow rivet and are secured in place as such; the bearing 9 is set with its head or plan surface end to the inside of the cap as at 10, the purpose of which will hereinafter appear.

The numeral 11 indicates a windlass shaft having a tight push fit in the bearings 8 and 9, and extending outwards somewhat beyond the side of the container body 1 where it is bent at right angles to itself to form a lever 12, the outer extremity of which is again bent into a loop 13. As a means for preventing the inadvertent movement of the lever 12 I bend the loop transversely as at 14, see Figure 5, to conform substantially to the periphery of the side wall 2 of the container and offset the lever adjacent the loop as at 15, so that when the lever is in axial alignment with the container body a resilient gripping pressure is exerted between the loop 13 and the side wall 2 of the container.

The numeral 16 indicates a piston having a skirt or side walls 17 of sufficient length to insure a parallel movement when being raised; this piston is superimposed with a bucket 18 having an upturned peripheral lip 19 and is preferably of some pliable material, so that as pressure is developed upon it incidental to the raising of the piston, the lip is adapted to form an effective seal against the side walls 2 of the container body. As a further means of preventing the passage of the grease or other matter to be dispensed by the container, I may fill the bucket with a wax or compound, preferably having no affinity to the grease, which would be of heavier consistency than the said grease, so that the pressure will be exerted through the wax upon the lip of the bucket. Secured centrally and on the upper surface of the piston 16 is a bale 20 which may be made from a piece of wire formed in a succession of loops as shown in Figures 1, 3 and 4, or as a cross member 21 whose outer extremities are bent downwards as at 22, see Figure 2, or by any other means whereby one or more cords, tapes or wires may pass freely around it without appreciable frictional loss. Attached by any suitable means to the bale 20 or 21, or about the shaft 11

is one end of a cord 23 which may be textile,

metallic or otherwise, as may be required to suit the material packed in the container and to meet the necessary strain imposed upon it; this wire extends in a succession of strands from the bale and over the shaft, the other end being passed through an orifice 24 in the shaft and knotted or otherwise secured thereto so that the desired purchase may be obtained. It will be noticed that the orifice 24 is formed relatively close to the bearing 9, see Figures 1, 2 and 3, and the initial windings 25 of the cord 23 extend therefrom in the direction of the bearing 9 so that as soon as the shaft 12 is rotated to dispense any of the contents and further windings of cord are made about the shaft which, being led towards the bearing crowds up against its head 10 and form a packing by which leakage through the bearing 9 is definitely prevented, subsequent rotation of the shaft 12 will build up a second row of windings which will add to the efficiency of the packing thus formed.

In the modification shown in Figure 3, I fit a parallel sided tubular spout 26 to which a suitable discharge nozzle 27 is attached, and to the piston 16 a tubular piston rod 28 having apertures 29 in its lower side walls. The piston rod has sliding movement in the spout 26 and maintains the piston at right angles to the container body walls, thus rendering it possible to form the piston as a flat disc 30, which would, at the time of filling the container, lie in contact with the bottom closure 3 thereof, thereby materially increasing the grease capacity. A further advantage of this construction is that the grease flow during discharge, is derived only from the lower area of the grease body and the friction developed in discharging is restricted to that caused by the grease flowing over the small areas of the inside of the tubular piston 28 and the discharging effort required upon the lever 12 is materially reduced, whereas in other forms of piston discharge the whole body of grease has to move upwards with the piston travel with a resultant skin friction equal to the greater area of the container side walls.

In the modification shown in Figure 4, a bale 31 is fitted within the discharge nozzle 7 to which it may be soldered or otherwise rendered leak proof. The top closure indicated by the numeral 32 is cupped and the piston 33 is cupped in a similar manner, the piston is provided with a skirt 34 to form a guide and is provided with a small rebate

35 at the top of the skirt to receive a suitable packing ring 36.

The numeral 37 indicates a bale upon the piston and 38 is a felt washer which seals a small orifice 39 through which, and the washer, the outer end of the winding cord 40 is threaded, the cord then passes through a slot 41 in the bottom closure 42 and is wound onto a shaft 43 which is journalled in opposite sides of the bottom rim 44 of the container side walls and outside the container body. By cupping the piston 33 the effective length for guiding purposes is increased and by cupping the top closure in the same manner as the piston, the contents of the container may be completely discharged at will.

What I claim as my invention is:

1. A container and grease gun comprising, a container, a closure for the container, provided with a discharge nozzle, bearings in said closure, a windlass rotatably mounted in said bearings extending outwardly beyond the side of the container and bent at right angles to form a lever arm, a handle loop on the extremity of said lever bent to conform to the contour of a wall of the container to grip said wall, a piston for the container and flexible connection means between the piston and said windlass shaft.

2. A container and grease gun comprising, a container, a closure for the container, provided with a discharge nozzle, bearings in said closure, a windlass rotatably mounted in said bearings extending outwardly beyond the side of the container and bent at right angles to form a lever arm, a handle loop on the extremity of said lever bent to conform to the contour of a wall of the container to grip said wall, a piston in the container, flexibly connected to the windlass shaft and a hollow piston stem having a plurality of orifices therein communicating with the discharge nozzle.

3. A device of the character described and in combination, a container provided with a piston and a discharge nozzle, a closure member communicating with the discharge nozzle, a windlass shaft flexibly connected to the piston and journalled in said closure member, means integral with said shaft without the container for operating it, and means integral with the aforesaid means for engaging with the container.

Dated at Vancouver, B. C., this 17th day of November, 1925.

WILLIAM H. G. GEAKE.
